UNITED STATES PATENT OFFICE

PETER PETERSON, OF DETROIT, MICHIGAN

PUNCH

Application filed March 21, 1930. Serial No. 437,725.

My invention has for its object to provide a punch which is so constructed that it may be readily removed from the retainer in a die head. The invention particularly relates to small punches that are removably connected to a head by a ball latch located in blocks or sockets in which the punches are stepped. As is well known in connection with such punches, where there are, as is commonly the case, a large number of punches for punching a plurality of holes in sheet material in a single stroke of the press, it is difficult to remove one or more of the punches owing to the fact that the stripper plate interferes with the engagement of the punch and prevents withdrawal of the punch from its socket. This is particularly true in view of the fact that the punches often break off, only leaving the shanks to grip. It has been customary to provide an opening for the insertion of a wire through the stripper plate and an opening in the socket to displace the ball from its latch engagement with the shank of the punch, but owing to the fact that the punches tightly fit the sockets, it is difficult to remove the punch from the socket even when the ball is pushed out of engagement. Dismantling of the stripper plate from the presser head is invariably required. By my invention, means is provided whereby the punch may be forcibly removed from the socket, though it may tightly fit therein.

The invention may be applied to punches of different forms and, to illustrate a practical application of the invention, I have selected two or three forms of punches embodying the invention and the punch removing tool to illustrate practical applications of the invention. The punches and the punch removing tool are described hereinafter.

Fig. 1 illustrates a fragmentary view of the punch die head and stripper plate and a punch removing tool located in position. Fig. 2 is an enlarged view of the punch illustrated in Fig. 1. Fig. 3 is an end view of

one form of punch. Fig. 4 is a view of a section taken on the plane of the line 4-4 indicated in Fig. 3. Fig. 5 is a side view of the punch illustrated in Fig. 3. Fig. 6 is an end view of a third form of punch. Fig. 7 is a view of a section taken on the plane of the line 7-7 indicated in Fig. 6. Fig. 8 is a side view of a punch shown in Fig. 6.

As is well known in connection with punching operations, many sheet metal structures require the formation of a large number of holes that are punched in a single stroke of the press. Sometimes a hundred or more holes are pierced in the sheet metal plate in each operation of the press. As shown in Fig. 1, the punch 1 is secured in a socket 2 that is connected to the die head 4 by means of suitable bolts 3, or dowl pins and bolts, to locate and secure the socket in proper position with reference to the other punches that may be connected to the head 4. A stripper plate 5 is commonly supported by means of the pins 6 which are slidable in the head 4 and are spring pressed, as by the springs 7. The stripper plate 5 operates to engage the sheet metal to be punched and secure it in position during the puncturing operation and until the punches leave the sheet metal that is operated upon. The springs 7 operate to hold the stripper plate 5 down until after the punches have been withdrawn from the sheet metal, in the manner well known in the art.

The punch 1 is held in position by means of the ball 10 that is located in a hole containing a spring 14 which operates to push the ball 10 towards the lower end of the hole 11. The hole 11 is bored at an angle to the hole 12 that forms the socket of the punch 1, and so as to form an opening between the holes 11 and 12 for the ball 10 to engage the shank of the punch 1. The opening is, however, sufficiently small to prevent the escape of the ball. The side of the punch 1 is provided with a concave surface 13, that is

adapted to engage the ball 10, and by reason of the pressure of the spring 14 to resist rotation of the punch 1. The line of the convex surface located in the plane extending 5 through the axis of the punch, slopes upwardly and away from the axis of the punch and, consequently, the ball 10, which seeks the greater depth of the concavity 13, also prevents the removal of the punch 1 that may be 10 caused by the frictional engagement of the punch in the sheet metal that is being operated upon by the punch during the withdrawal of the press.

The spring pressure against the ball 10 resists such turning movement of the punch 1, and, inasmuch as it is necessary that the shank of the punch 1 should fit quite closely the socket 2, it has been found that the frictional engagement between the socket and the shank 20 of the punch 1 also prevents longitudinal movements of the punch 1 in withdrawing the punch from the socket. This is particularly true where the punch is broken off. Also, owing to the close proximity of the 25 stripper plate 5 to the presser head, and on account of the size or area of the stripper plate, and in view of the fact that, as a rule, a large number of such punches are distributed over the area of the stripper plate, it 30 is practically impossible to remove any of the punches when they have broken.

To unlock the ball latch, a wire is inserted in aligned openings, such as the opening 15 formed in the stripper plate 5, and the opening 16 formed in the block or socket 2. The opening 16 extends to the hole 11 in which the ball 10 is located. The ball is lifted from the engagement with the punch by the wire and when an effort has been made to engage 40 the punch with pinchers, at a point between the socket 2 and the stripper plate 5, such efforts have usually been unsuccessful and, owing to the large number of punches and the difficulty experienced in reaching the 45 punches, it has invariably been found necessary to remove the stripper plate from the press head.

By my invention the punches are provided with a rounded thread 18 having considerable 50 pitch. The rounded thread has a rounded crown and a rounded valley that conforms to a sine curve in cross section in the plane through the axis of the punch. This eliminates all sudden changes in the direction of 55 adjoining surfaces and prevents fracture which would otherwise occur in the corners. This is of particular value where the punches are small. For the removal of the punches, a tool 17, having a female thread 19, corresponding in shape and size to the male that 60 is formed on the punch, is used. The exterior diameter of the portion of the tool is slightly less than the diameter of the opening 20 in the stripper plate 5 through which the 65 punch moves in operating upon the work.

Whereby, the end of the tool 17 may be readily inserted through the stripper plate and rotated to engage the thread 18 of the punch. Preferably, the tool is provided with a handle 70 22, whereby it may be, not only readily turned to securely connect the tool 17 with the punch, but also to draw the punch from the die head. The concavity 13 is also preferably so formed that the punches may be turned by the tool, by a pressure exerted on the handle, to force the 75 ball 10 upwards in the opening 11 as the concave recess 13 is moved away from the ball 10 and until the ball 10 rides on the cylindrical surface of the shank of the punch 1, whereupon the punch 1 may be forcibly drawn from the socket 2. The surfaces 9 of the concavity preferably slope from the center of the concavity. The handle 22 affords a means for gripping the tool to rotate, with considerable torque, to disengage the ball and withdraw the punch, notwithstanding the tight fit of the punch in its socket. Thus, any one of a large number of punches may be readily removed from the die head without removal of the stripper plate.

Where the punches have an oblong cross section, such as that shown in Figs. 2, 3, and 4, the thread may be formed only on the portions of the surfaces that are located at distances from the axis of the punch that are greater than the other portions of the surfaces, such as, the thread may be formed only on the portions 25 of the punch 26, since such portions protrude farther from the axis of the punch than the portions 27. The construction also may be applied to a square punch, such as that shown in Figs. 6, 7, and 8, in which case the thread 29 may be formed above the square end 30 of the punch and intermediate the shank and the square end. 100 The tool 17 may be provided with the female thread that corresponds to the female thread 25 and 29 and the tool may be inserted through the stripper plate and rotated to engage the punches and remove them in a manner indicated in Fig. 1.

I claim:

In combination with a ram and a stripper plate, the stripper plate connected to the ram for short limited movements relative to the ram, the stripper plate having an opening, a punch having a shank at one end and a shearing edge at the other end, the punch located in and projecting through the opening, the ram having a socket, a ball latch located in 115 the ram for securing the punch in the socket of the ram, the shank of the punch having a sloping concave surface operable by rotative movement of the punch to force the ball away from the axis of the punch to release the 120 punch from the ball latch, a spring for pressing the ball against the surface of the punch, at a point located at the bottom of the concavity, the punch having a spiral corrugation 125 located on the shank and below the ram and 130

normally above the lower surface of the stripper plate and adapted to receive a tool having a spiral corrugated surface fitting the corrugated surface of the punch and insertable through the said opening and adapted to engage the punch by rotation and rotate the punch to disengage it from the ram and withdraw the punch through the opening of the plate.

10 In witness whereof I have hereunto signed my name to this specification.

PETER PETERSON.
